UNITED STATES PATENT OFFICE.

ALONZO ALDRICH, OF BELOIT, WISCONSIN.

PAPER-DRYING MACHINE.

1,139,625.

Specification of Letters Patent. Patented May 18, 1915.

Application filed February 24, 1914. Serial No. 820,479.

To all whom it may concern:

Be it known that I, ALONZO ALDRICH, a citizen of the United States, and a resident of Beloit, in the county of Rock and State of Wisconsin, have invented certain new and useful Improvements in Paper-Drying Machines; and I do hereby declare that the following is a full, clear, and exact description thereof, reference being had to the accompanying drawings, and to the letters of reference marked thereon, which form a part of this specification.

This invention relates to paper drying machines having drier rolls or cylinders arranged in groups or sets and supported by sectional frame members arranged in groups or sets corresponding in number to the groups of drying rolls.

The principal object of the invention is to provide a simple, economical and efficient machine comprising a plurality of groups or sets of drying rolls four tiers high and a roll-supporting frame formed of a plurality of groups or sets of sectional frame members adapted to be added to or reduced in number, as desired, and to form a strong and rigid frame of any desired size according to the number of groups or sets of rolls to be supported and operated.

Further objects of the invention are to provide a machine comprising duplicate groups or sets of drying rolls each four tiers high, a frame formed of sectional frame members and suitable driving and connecting gear mechanism, all adapted to enable paper to be passed through each series of rolls in the same manner and in a direction which will enable the paper to come into contact with a large area of the surface of each roll; to enable rolls to be arranged and operated in groups or sets each having four superposed tiers, the sets of sectional frame members corresponding in number to the duplicate sets of drier rolls.

Other and further objects of the invention will appear from the following description and claims and from an inspection of the accompanying drawings which are made a part hereof.

The invention consists in the features, combinations, and details of construction herein described and claimed.

In the accompanying drawings, Figure 1 is a view in elevation of a machine constructed in accordance with my invention and improvements; Fig. 2, a plan view of a

portion of the machine shown in Fig. 1; and Fig. 3, a view in transverse section, taken on irregular line 3 of Fig. 1 looking in the direction of the arrow. Fig. 4, an enlarged detailed view in elevation, showing the adjusting screw mechanism for securing bearing boxes in adjusted position and permitting the adjustment thereof.

In making a machine in accordance with my invention and improvements, I provide a main frame which comprises in its construction a plurality of duplicate sectional lower frame members *a* and *b* which with the end frame members *c* form the bottom tiers or rows of sectional frame members upon which are supported intermediate sectional frame members *d* which are made in duplicate and each of which forms a support for an upper section of the frame member *e*. All of the sectional frame members *a*, *b*, *c*, *d*, and *e* are made in pairs, the members of each pair being opposite each other and all arranged to form a back frame and a front frame. The lower sectional frame members *a* and *b* are each approximately U-shaped. The members *a* each have a pair of transversely extending arm portions *f* which are integral with a base portion and are spaced apart so as to admit therebetween a journal box or bearing *g* which is supported upon the base portion. The frame members *b* each have a pair of similar arms or upright frame portions *f'* projecting upward from an integral base which forms a support for a journal box or bearing *g* located between such arms. All of the journal boxes for supporting drier rolls may be of identical construction and they are therefore all designated by the same reference letter, in order to avoid prolixity. The adjacent arms *f* and *f'* have spaces *h* therebetween adapted to enable journal boxes or bearings *i* to be mounted upon arms *k* and *l* which project laterally from the upright arm portions *f* and *f'* of adjacent sectional frame members *a* and *b*. Each sectional frame member *d* has legs or bottom portions *m* which have spaces *n* therebetween adapted to admit the journal boxes or bearings *g* which constitute the second series of such boxes and form supports for the second row of drying rolls hereinafter described, said boxes being supported by or upon the upper ends of frame members *f* and *f'* of the corresponding lower sectional frame members. Each of the frame members *d* is also pro-

vided with a roll-supporting arm or upper frame portion *o* adapted to form a support for a journal box *g* of a third series or row of such boxes, for supporting a third tier 5 of drier rolls hereinafter described. An upper central or main body portion *p* of each sectional frame member *d* is adapted to form a support for a journal box *g* located in the same horizontal plane with the journal 10 box supported upon the frame portion or arm *o*. Each of the sectional frame members *d* also has a central space or aperture adapted to admit a journal box *v* which is supported upon a central horizontal frame 15 portion or arm *v'* intermediate the approximately U-shaped connected portions or legs *m*.

Each of the upper sectional frame members *e* has an approximately U-shaped main 20 body portion comprising lower frame portions or legs *q* which are spaced apart so as to provide a space *r* adapted to admit a journal box or bearing *g* which is supported therebetween upon the upper portion *p* of 25 a corresponding intermediate frame member *d*, as already described, each of said sectional frame members *e* also having upper roll-supporting portions or arms *s* which are integral with the approximately U-shaped 30 body portion and adapted to form supports for journal boxes or bearings *g* located above and supported by said frame portions *s*, which boxes are adapted to form supports for the top row of drier rolls hereinafter 35 described.

At the extreme end of the machine sectional end frame members *c*, each having an upper end portion *t*, similar to the parts *f* and *f'* of the frame members *a* and *b*, 40 serve to support the outermost end portion of the corresponding intermediate frame members *d*. The members *c* are also each provided with a horizontal arm *u* adjacent to a similar horizontal arm *k* and adapted to 45 coöperate with the latter in supporting a journal box *i* located in the same horizontal plane with other similar journal boxes which in other parts of the machine are supported by similar arms *k* and *l*, as already described.

50 The sectional frame members *a*, *b*, *c*, *d*, and *e*, respectively, are made and arranged in pairs, as already suggested, the members of each pair being opposite each other at or adjacent to opposite ends of the drier rolls 55 to be supported thereby and the journal-box-supporting portions or arms of each pair are opposite each other and in position to support journal boxes in alinement at opposite ends of the drier rolls to be supported by the 60 journal boxes, thus forming a back frame and a front frame of the machine.

65 The machine frame thus formed may comprise any desired number of groups or sets of sectional frame members, each comprising a pair of top frame members *e*, a pair of in-

termediate frame members *d* upon which the frame members *e* are supported, and a pair of bottom frame members *a* located intermediate a pair of bottom frame members *b* and in supporting engagement with the intermediate frame members *d* in each group or set, with the exception of the end groups in which the bottom end frame members *c* are employed, in positions corresponding with the positions of the frame members *b* in the intermediate groups or sets. The bottom frame members *b* arranged intermediate the bottom frame members *a* serve to connect the groups or sets of frame members, and the top frame members *e* of adjacent groups may be connected by means of tie-rods or braces *w* which need only be used at the back of the frame, said braces having their opposite ends removably secured to the frame members *e* to be connected thereby, by means of bolts or other suitable securing means.

Mounted in each group or set of sectional frame members is a group or set of drier rolls each comprising rolls 2, 3, 4, 5, 6, 7, 8 and 9, the roll 2 being provided with journals 2' at its opposite ends rotatably mounted in journal boxes *g* supported by the bottom sectional frame members *a*. The rolls 3 have journals 3' and the rolls 8 have journals 8' at opposite ends thereof. The rolls 4 are provided at each end with journals 4' and the rolls 5 with similar journals 5'. The rolls 6 are each provided at the opposite ends thereof with journals 6', and the rolls 7 with journals 7', and each roll 9 is provided with journals 9' at the opposite ends thereof, all of said journals being rotatably supported in journal boxes *g* which are in turn supported by the sectional frame members *a*, *b*, *c* and *d*, as shown in the drawings.

70 A suitable form of driving mechanism for driving the drying rolls, such as that shown in the accompanying drawings, may comprise a main drive shaft 10 which is mounted in suitable bearings 11 and adapted to be operatively connected with a suitable source of power. A counter-shaft 12 rotatably mounted in suitable bearings 13 is provided with a gear wheel 14 upon and rotatable with said shaft and adapted to be operatively connected and driven by means of a suitable gear wheel 15 mounted upon and rotatable with the main driving shaft. Said gears may be of any desired form and the counter-shaft or main drive shaft may be of any ordinary or well known form. The counter-shaft is operatively connected with transverse driving shafts 16 by means of suitable gearing or connecting mechanism which may be of any desired type and which 110 when constructed as shown in the drawings comprises a pinion 17 on the shaft 12 in toothed engagement with a gear or pinion 18 on and rotatable with a shaft 19, said shaft 19 being rotatably mounted in suitable bear- 115 120 125 130

ings 20 and provided with a pinion 21 fixed to said shaft and in toothed or operative engagement with a gear wheel 22 which is mounted upon and rotatable with the corresponding shaft 16. Any desired number of shafts 16 may be employed as required according to the size of the machine or the number of rolls to be operated, and the shafts 16 are adapted to be connected with any suitable source of power either by means of a shaft 12 for operating a plurality of shafts 16, or by other suitable connecting means.

The shafts 16 are each mounted in suitable bearings 23 and 24 and are each provided with a driving pinion 25 which is rotatable with the shaft and in toothed or operating engagement with a gear 26 secured in fixed relation to a drier roll 2 of the corresponding group or set of drier rolls to be driven by the pinion or in engagement with which the driving pinion 25 is mounted. Each of the drier rolls 2, 3, 4, 5, 6, 7, 8 and 9 of the respective groups or sets of rolls of the machine is provided with a toothed gear wheel 26 secured in fixed relation to and rotatable with said rolls, respectively. These gear wheels 26 of all of the drier rolls are all of identical construction and are in the form of ordinary toothed spur gear wheels. These gears of all of the drier rolls are therefore, for the sake of brevity and clearness, designated by the same reference numeral.

In each alternate group or set of drier rolls the gear 26 of the drier roll 2 of such group or set is in toothed engagement with the corresponding driving pinion or gear wheel 25, as already suggested. The pinion 25 is also in toothed engagement with the gear 26 of the drier roll 3 of the same or corresponding group or set of rolls. The gear wheel fixed to or rotatable with the drier roll 3 is in toothed engagement with the gear which is fixed to the drier roll 4 and is also, by preference, in toothed engagement with an intermediate toothed pinion 27 operatively connected with the same group or set of rolls, which last mentioned pinion is mounted upon a supporting stub shaft 28 journaled in suitable bearings *v*, as already suggested, and in toothed engagement with the adjacent spur gear 26 which is fixed to or rotatable with the drier roll 5. The corresponding gear 26 fixed to the roll 5 of each group, respectively, is in toothed engagement with a similar gear fixed to and rotatable with the roll 6 and is also in toothed engagement with a similar gear 26 fixed to and rotatable with the roll 7 of the same group or set of rolls. The driving pinion 25 may also be in toothed engagement with a similar gear 26 fixed to and rotatable with the roll 9 of the next adjacent group or set of rolls, and the said gear for the roll 9 may be mounted in toothed en-

gagement with a similar gear on or fixed to and rotatable with the adjacent roll 8 of the last mentioned group or set of rolls. It will thus be seen that by rotating the driving gear 25 in a direction opposite to the direction of movement of the hands of a clock, the adjacent drier roll 2 will be caused to rotate in the opposite direction. The main driving gear 25 being in toothed engagement with the gears fixed to the adjacent drier rolls 2, 3 and 5 of the corresponding group and to the gear fixed to the adjacent drier roll 9 and the gears of all of the drier rolls in each group of rolls operatively connected with such a driving gear being operatively connected as described, the drier rolls will be caused to rotate in the directions indicated by the arrows in Fig. 1, and will feed a strip of paper 31 between the rolls of each set in the directions indicated by the arrows in said figure. In each alternate group or set of rolls an intermediate pinion 29 mounted upon a shaft or journal 30, which is rotatably supported in journal boxes *i*, hereinbefore mentioned, may be used in lieu of the primary or main driving pinion 25, as indicated in Fig. 1. The intermediate pinions 29 are, by preference, mounted upon shafts 30, as already suggested, which by preference extend transversely through the machine or from the front frame to the back frame, and have their ends journaled in both frames. The intermediate pinion 27, however, is shown mounted upon a stub shaft 28 which is adapted to be suitably supported by means of a bearing *v*, as indicated in Fig. 3, said bearing being of sufficient length to afford a suitably firm and strong support without the necessity of extending the shaft 28 through the machine or to the other frame of the machine.

The intermediate gear 27 of each or any desired number of the groups of rolls is adapted to be employed as the main driving pinion or gear for such group of rolls and that when so employed the main driving pinion 25 of such group of rolls may be driven or may serve as an intermediate pinion as desired.

The bearings *v*, and also the bearings or journal boxes *g*, are each provided with adjusting mechanism comprising a pair of adjusting screws 32 in threaded engagement with the base portions of said bearings or boxes, respectively, on opposite sides thereof, said screws having heads 33 adapted to abut against shoulders 34 in the adjacent sectional frame members and between which shoulders the bearings are located. A lock-nut 35 is mounted in threaded engagement with each adjusting screw and is adapted to hold the adjusting screw in any position to which it is adapted to be adjusted. The bearings *v* are provided with securing bolts 36 inserted in suitable openings

in the sectional frame members and adapted to securely hold the bearings, and thereby the journals and gear mechanism supported by said bearings or bearing boxes, 5 in operative position. The bearings *g* are also each secured in a similar manner to the sectional frame members which form supports therefor by means of similar securing bolts 37, which are inserted through suitable 10 openings in the frame members upon which said bearing boxes are mounted. The adjusting mechanism or adjusting screws for each journal bearing or journal box, respectively, may be of identical construction (see 15 Fig. 4), and it is, therefore, deemed unnecessary to show these connections in all of the great number of instances in which they occur, or to illustrate in detail the constructions for more than one form of the bearing 20 boxes. Filler plates 38 are mounted beneath the bearing boxes *g* for such drier cylinders as are to be supported in a somewhat higher position than other cylinders of the same series. The drier cylinders are thus enabled 25 to be adjusted and supported in proper operative position with the required gear wheels in toothed operative engagement, so as to cause each of the drier cylinders to rotate in the desired direction, all in such a manner 30 that the journal boxes used may be of identical construction, and the removably connected sectional frame members may be of the desired uniformity of construction and interchangeable, and may be of dimensions 35 which are not required to vary in order to enable the desired adjustments to be obtained.

The sectional frame members *a*, *b*, *c*, *d* and *e* are removably secured together, as already 40 suggested, by means of screw bolts 39, as indicated in Figs. 1 and 3, said bolts being inserted through openings 40 in the frame members, said openings 40 being of somewhat larger diameter than the bolts, and 45 adapted to permit such adjustment of the frame members, with respect to one another, as may be found desirable for any reason, for instance, on account of irregularities in form due to shrinkage or other causes.

50 The means for connecting sectional members *a*, *b*, *c*, *d* and *e* of the respective sets or groups, are the same in each instance.

The mating frame members being in the form of "rights and lefts", it is deemed 55 unnecessary to show the back view of the machine frame which corresponds in all substantial respects with the front view shown in Fig. 1.

Each set or section of cylinders, when 60 constructed and arranged as herein shown and described, comprises, by preference, eight cylinders arranged in four superposed tiers, each tier comprising at least two cylinders, as already suggested; the axes of the 65 cylinders of the second tier being offset lat-

erally to one side with respect to the axial centers of the cylinders of the first tier, the axial centers of the third tier being offset laterally in the opposite direction or on the opposite side of the axial centers of the 70 cylinders of the second tier, and the axes of the cylinders of the top tier being offset laterally with respect to the axial centers of the cylinders of the third tier, so as to be directly over the cylinders of the second tier. In other words, the cylinders of the 75 second and third tiers are offset in the same direction with respect to the axial centers of the adjacent cylinders of the first and second tiers.

80 In operation, the sheet or strip of paper to be operated upon is threaded into position to engage and extend between the cylinders and in engagement with and part way around each of the cylinders, and extends in each set between a cylinder 4 in the third tier and an adjacent cylinder 3 in the second tier; between the latter and a cylinder 6 in the fourth tier, being stretched directly from said cylinder 3 to said cylinder 6; between the cylinder 6 and an adjacent second cylinder 5 in the third tier; between the latter and an adjacent second cylinder 7 in the fourth tier; between the latter and a cylinder 2 in the bottom tier, 95 being stretched directly from said cylinder 7 to said cylinder 2; between the latter and a second cylinder 8 in the second tier; between said cylinder 8 and a second cylinder 9 in the bottom tier; and between said cylinder 9 and a cylinder of the next adjacent tier which, as shown in the drawings, is cylinder 4 in the third tier of an adjacent set and corresponds with cylinder 4 of each set of cylinders. It will thus be seen that the 100 strip of paper is threaded between the cylinders of each set in the same manner, so that its direction of movement through each set is a repetition of its direction of movement through the preceding set or sets, and 105 that the driving mechanism is so constructed and arranged as to connect and drive all of the cylinders in operative feeding engagement with the strip of paper and in the direction necessary to cause the paper to move 110 with and between the peripheries of the cylinders in the order above mentioned and in the direction indicated by the arrows, or the reverse.

115 From the foregoing it will be seen that 120 the construction and arrangement of the driving mechanism, the rolls, and the sectional frame members constituting the respective groups of said members is such as to enable the machine as a whole to be built 125 higher than has heretofore been found practicable and to occupy the minimum amount of space lengthwise of the machine in proportion to the capacity thereof or in proportion to the length of the web or paper 130.

subjected to the simultaneous action of the rolls or extending from the receiving end to the discharge end of the rolls or machine as a whole, and that any desired number 5 of groups or sets of rolls, sectional frame members, and suitable driving mechanism therefor may be built up or arranged in sections, groups, or units, the number of which may be increased or decreased, as desired, 10 according to the capacity required. The arrangement is such that the stresses and strains upon the driving mechanism for the rolls for the respective groups and the connected gears or trains of gears for such rolls 15 will be distributed so as to enable the rolls to be operated without unnecessary or excessive expenditure of power.

Other and further advantages derived from applicant's construction are: in providing separable, four-tier units, each of which in operation imparts a maximum drying effect to the paper without necessitating the use of auxiliary rollers; a simple driving mechanism, which drives each roll 25 in the proper direction; and each of said separable units being so constructed that they may be added together by simply connecting their respective driving mechanisms, thereby materially increasing the size of the 30 machine without necessitating either the rearrangement of the driving elements, or alteration of the path which the paper takes through the machine.

I claim:

- 35 1. In a machine of the class described, the combination of a frame, a set of drying cylinders comprising four tiers of cylinders rotatively supported by the frame, each tier comprising at least two cylinders spaced 100 apart with respect to each other and with respect to the cylinders of the adjacent tiers, the cylinders in the second and fourth tiers having their axial centers offset laterally with respect to the axial centers of the adjacent cylinders of the first and third tiers, each of said cylinders being provided at one end with a gear wheel concentric therewith, a pinion pivoted equidistantly from the axes of and meshed with the two gear wheels in the 105 first tier and the adjacent gear wheel in the second tier, a second pinion pivoted between the cylinders of the second tier and equidistant from the axes of the adjacent gear wheel in the third tier and the aforesaid pinion-connected gear wheel in the second tier, said pinions being operatively engaged with said gear wheels in the second and third tiers and both gear wheels in the first tier so as to turn all of their respective cylinders in the same direction, and 110 each of the remaining four cylinders having their gears meshed directly with an adjacent pinion-connected gear so as to turn its respective cylinder in the opposite direction, and driving means connected with one of 115 said pinion gears for operating all of said cylinders, said cylinders being so arranged and driven as to operatively engage a strip of paper threaded in engagement with and part way around each cylinder. 120
- 40 2. In a machine of the class described, the combination of a plurality of sets of parallel rotary cylinders, each set comprising four superposed tiers of cylinders, each 125

tier comprising at least two cylinders spaced apart with respect to each other and with respect to the cylinders of the adjacent tiers, the cylinders of each tier having their axial centers offset laterally with respect to the 70 axial centers of the adjacent cylinders of the next adjacent tiers, all of said cylinders being constructed and arranged in position to operatively engage a strip of paper threaded between the cylinders and part way 75 around and in engagement with a cylinder in the first tier of each set and extending between said cylinder and a cylinder in the third tier, between the latter cylinder and an adjacent cylinder in the second tier, between the latter cylinder and a cylinder in the fourth tier, between the latter and an adjacent second cylinder in the third tier, between the latter and an adjacent second cylinder in the fourth tier, between the latter and a second cylinder in the first tier, between the latter and a second cylinder in the second tier, and into position to engage a cylinder in the next adjacent set of cylinders, a set of sectional frame members for 80 each set of drying cylinders and in supporting engagement with the latter, means for securing the sectional frame members together in sets, and driving mechanism operatively connected with and acting to rotate all of said cylinders. 85

3. In a machine of the class described, the combination of a frame, a set of drying cylinders comprising four tiers of cylinders rotatively supported by the frame, each tier comprising two cylinders, the cylinders in the second and fourth tiers having their axial centers offset laterally with respect to the axial centers of the adjacent cylinders of the first and third tiers, each of said cylinders being provided at one end with a gear wheel concentric therewith, a pinion pivoted equidistantly from the axes of and meshed with the two gear wheels in the 100 first tier and the adjacent gear wheel in the second tier, a second pinion pivoted between the cylinders of the second tier and equidistant from the axes of the adjacent gear wheel in the third tier and the aforesaid pinion-connected gear wheel in the second tier, said pinions being operatively engaged with said gear wheels in the second and third tiers and both gear wheels in the first tier so as to turn all of their respective cylinders in the same direction, and 105 each of the remaining four cylinders having their gears meshed directly with an adjacent pinion-connected gear so as to turn its respective cylinder in the opposite direction, and driving means connected with one of 110 said pinion gears for operating all of said cylinders, said cylinders being so arranged and driven as to operatively engage a strip of paper threaded in engagement with and part way around each cylinder. 115

4. In a machine of the class described, the combination of a frame, a plurality of sets of drying cylinders rotatively supported by the frame, each set comprising four tiers of 5 two cylinders each, the cylinders in the second and fourth tiers of each set having their axial centers laterally offset with respect to the axial centers of the adjacent first and third tiers, each of said cylinders being provided with a gear wheel concentric therewith, each set having two gear pinions mounted on the frame, one of which 10 enmeshes with the two cylinder gears in the first tier and the adjacent gear in the second tier, the other pinion positioned between the cylinders in the second tier and enmeshed with said cylinder gear in the second tier and the adjacent cylinder gear in the 15 third tier, so that all four of said cylinder

gears are adapted to turn in the same direction, the remaining four cylinder gears in each set being directly enmeshed each with an adjacent pinion-driven cylinder gear so as to turn in the opposite direction thereto, means for connecting the plurality of sets together, and driving mechanism operatively connected with and acting to rotate all of the cylinders, so connected, in operative engagement with a strip of paper trained part way around each cylinder. 20 25 30

In testimony, that I claim the foregoing as my invention I affix my signature in the presence of two witnesses, this 19th day of February A. D. 1914.

ALONZO ALDRICH.
